UNITED STATES PATENT OFFICE.

PAUL M. BEARD, OF ST. LOUIS, MISSOURI, ASSIGNOR TO AMERICAN CAR AND FOUNDRY COMPANY, OF ST. LOUIS, MISSOURI, A CORPORATION OF MISSOURI.

CAR-DOOR.

1,008,774.

Specification of Letters Patent. Patented Nov. 14, 1911.

Application filed May 25, 1910. Serial No. 563,430.

To all whom it may concern:

Be it known that I, PAUL M. BEARD, residing at St. Louis, Missouri, and being a citizen of the United States, have invented 5 certain new and useful Improvements in Car-Doors, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof will occur to persons skilled in the art.

In said drawings: Figure 1 is a view in side elevation of a fragment of a car illustrating an embodiment of the present invention applied thereto. Fig. 2 is an enlarged, detail, fragmentary view illustrating one of the hangers in elevation. Fig. 3 is a vertical section therethrough, taken on the plane indicated by line 3—3 of Fig. 2. Fig. 4 is a horizontal section therethrough, taken on the plane indicated by line 4—4 of Fig. 2. Fig. 5 is a detail fragmentary view of a further embodiment of the invention.

Referring to the drawing by numerals, 1 is a side wall of a car formed with a doorway 2, adapted to be closed by a sliding door 3 suspended from a track or way extending above, across, and beyond the doorway. 20 The said track preferably consists of a Z section 4 having its web disposed horizontally and its inner flange upstanding and bolted or otherwise suitably secured to the side wall of the car. Bolted or otherwise fixed to the door 3, near the upper edge thereof, are hanger brackets 5—5, each comprising a plate engaging the outer surface of the door 3, an arm upstanding from the plate and a housing extending laterally toward the car from the upper end of the arm and over-hanging the web of the Z section comprising the track. In each of said housings is mounted a roller bearing 6 having laterally extending bearing members 7 engaging guiding pockets 8—8 formed in the opposite walls of the housing. The housing is relatively narrow for accommodating the width of roller 6, but, as clearly indicated in Fig. 2, the housing is elongated in the direction of the travel of the door, and the

pockets 8 are correspondingly elongated for permitting a limited amount of independent travel of the respective roller 6 during operation. The rollers 6 rest upon the upper surface of the track or way and sustain the 60 hangers which in turn sustain the door, and, to limit lateral shifting of the door, during its edgewise travel, a roller 9 is disposed horizontally and revolvably connected to the upper edge of the door contiguous to each 65 bracket 5 and beneath the web of the Z section, being positioned for at times engaging the inner surface of the depending outer flange of the Z section, and thus limiting outward lateral play of the door. It is to 70 be observed that necessity for providing means for preventing roller 6 from leaving the track or way laterally is thus obviated, and at the same time frictional contact of the door 3, with either the side wall of the car or the said depending flange of the Z section, is prevented. Each roller 9 may be connected to the upper edge of the door in various ways, but preferably by an upstanding spindle or shaft 10 formed integral with or fixed to a U shape connecting plate 11 inclosing the upper edge of and riveted to the door 3.

The upper end of each shaft 10 extends beyond the upper surface of the respective 80 roller 9 into a position for engaging the inner edge of a wedge block 12 fixed to the under portion of Z section 4, there being one block 12 for each shaft 10, and each block being formed with an inwardly beveled or diagonal edge 12^a terminating at its inner end in a straight portion 12^b. Above the doorway 2, and extending along the path of travel of the rollers 9, a wearing strip 13 may be provided forming an inner 90 limit for the edgewise shifting of the rollers 9. Any suitable closing wedge brackets 14—14 may be provided for engaging and confining the lower edge of the door 3.

In operation, the door 3 is shifted edgewise to and from a position closing the doorway, and, in traveling outwardly or to an open position, the shafts 10 slide longitudinally of wedge blocks 12 until freed from the same, and then the door moves 100 edgewise practically free from friction, being sustained by the hangers 5 and rollers 6 engaging the track or way, and retained against frictional contact with contiguous parts by rollers 9. In closing the door, the 110

door is slid edgewise until the shafts 10 engage the outer ends of the diagonal edges 12^a of wedge blocks 12, and then, as the door is moved into a closed position, said shafts are forced laterally toward the door frame with a resultant inward lateral shifting of the upper edge of the door to a snugly closed position. As the door arrives in this closed position, the shafts 10 arrive in engagement with relatively straight edges 12^b of wedge blocks 12, and the door, being locked, is thus retained against any lateral shifting during transit.

A facing strip 15 or a portion of the door 15, jamb extends outwardly at each side of the doorway, and the door 3 is freely movable between the depending flange of Z section 4 and the strip 15 at one side of the doorway until the shafts 10 engage wedge blocks 20 12, whereupon the door is wedged laterally over into firm contact with strips 15 so as to be held against play during transit. The straight edge portions 12^b which are engaged by shafts 10 when the door is completely closed obviate any tendency of the door to ride edgewise out of place, such as would exist if the shafts 10 were left in engagement with inclined or beveled surfaces. Each roller underlaps the respective block 25 12 which its shaft engages, thus largely obviating liability of vertical rocking of the movable parts. The door is thus provided with two distinct sets of guiding elements, being the rollers 9, which guide the door 30 when loose and free to have limited lateral play, and the shafts 10, which guide the door to a tightly closed position.

The shaft 10 which upstands from the upper edge of door 3 may be carried, as indicated in Fig. 5, by an angle plate 11^a which is fixed to or formed integral with bracket 5, plate 11^a extending across the upper edge of and engaging the door. Obviously additional means of attachment of plate 11^a to the door 3 may be provided, but usually its connection with bracket 5 is sufficient. A fillet or web 11^b may be provided for stiffening the connection between the horizontal and vertical legs of plate 11^a.

50 What I claim is:

1. In a door structure, the combination, with a track, a door hanger engaging the same, a door sustained by said hanger, a shaft upstanding from the door, and a wedge block disposed in the path of the

shaft for effecting lateral shifting thereof during edgewise travel of the door and a roller coaxial with the shaft and disposed for underlapping the wedge block.

2. In a door structure, the combination, 60 with a track, of a hanger engaging the same, a door sustained by said hanger, a wedge block sustained by said track and having a diagonal edge, means upstanding from the door in position for engaging said diagonal edge and being shifted laterally thereby, and correspondingly shifting the door during edgewise travel of the door, and a roller carried by said upstanding means and adapted to underlap the wedge block. 70

3. In a door structure, a Z section track, a door hanger engaging the same, a door sustained by said hanger, a horizontally disposed roller carried at the upper edge of the door in position for engaging one of the 75 flanges of the track section, a closing wedge for the door out of the path of the roller, and guiding means carried by the door additional to the roller adapted to engage the closing wedge. 80

4. In a door structure, the combination, 85 with a track and a hanger engaging the same, of a door sustained by said hanger, a shaft fixed to and upstanding from the door, a horizontally disposed roller journaled on the said shaft, and a wedge block disposed in the path of travel of the shaft for shifting the shaft laterally during edgewise travel of the door, the wedge block being out of the path of the roller. 90

5. In a door structure, the combination, 95 of a Z section track, a door slidably sustained thereby, a shaft extending from the door, a roller on said shaft disposed for engaging one of the flanges of the track section for limiting lateral play of the door, and a wedge block in the path of movement of the shaft during edgewise travel of the door, the shaft extending beyond the roller in position for engaging the block for being 100 shifted laterally and correspondingly shifting the door, the wedge block being out of the path of the roller. 100

In witness whereof I have hereunto set my hand in the presence of two witnesses. 105

PAUL M. BEARD.
